CLAIM

The ornamental design for a battery terminal extension tab, as shown and described.

DESCRIPTION

FIG. 1 is a perspective view of a battery terminal extension tab;

FIG. 2 is a front elevational view thereof;

FIG. 3 is a left side elevational view thereof, the right side elevational view being a mirror image;

FIG. 4 is a top plan view thereof;

FIG. 5 is a bottom plan view thereof;

FIG. 6 is a perspective view of a second embodiment of a battery terminal extension tab;

FIG. 7 is a front elevational view thereof;

FIG. 8 is a rear elevational view thereof; and,

FIG. 9 is a perspective view of thereof shown in use.

(Continued)

The broken lines shown represent unclaimed subject matter
and form no part of the claimed design.
